UNITED STATES PATENT OFFICE.

RAOUL J. PARATORE, OF NEW ORLEANS, LOUISIANA.

PAPER CUTTING AND PASTING MACHINE.

Application filed July 30, 1923. Serial No. 654,758.

To all whom it may concern:

Be it known that I, RAOUL J. PARATORE, a citizen of the United States, and resident of New Orleans, in the parish of Orleans and State of Louisiana, have invented certain new and useful Improvements in Paper Cutting and Pasting Machines, of which the following is a specification.

This invention relates to paper cutting and pasting machines especially adapted for use in connection with wall paper.

Briefly stated an important object of this invention is to provide a machine of the character specified by means of which wall paper may be pasted and cut longitudinally simultaneously so as to overcome the necessity of pasting the paper by hand as is now done.

A further object is to provide simple means whereby the machine may be adjusted to properly guide and cut the paper to the desired width.

A further object is to provide a machine of the character described which may be conveniently transported and set up for operation and which is extremely simple to operate.

A further object is to provide a machine of the character specified which is of highly simplified construction, durable in use and cheap to manufacture.

Other objects and advantages will be apparent during the course of the following description.

35 In the drawings, forming a part of this application and in which like numerals are employed to designate like parts throughout the same.

Figure 1 is a side elevation of the improved machine set up for operation.

Figure 2 is a front elevation of the same.

Figure 3 is a plan view of the machine.

Figure 4 is a vertical transverse sectional view through the same.

45 Figure 5 is a detail sectional view illustrating the means to support a roll of paper in the machine.

Figure 6 is a perspective of a cutter embodied in the invention.

50 Figure 7 is a perspective of a measuring device embodied in the invention.

In the drawing wherein for the purpose of illustration is shown a preferred embodiment of the invention, the numeral 5 generally designates a frame of rectangular formation and having its rear side formed with

a pair of attaching arms 6 formed with gripping members or sockets 7 for the reception of a supporting member 8. The attaching members 6 support the rear side of the frame 60 while the forward side of the frame is supported by means of legs 9 having pivotal connection with the frame. Figure 2 illustrates that the lower portions of the legs 9 are connected as indicated at 10 with bracing links 11, the adjacent portions of which are overlapped and are pivotally connected as indicated at 12.

When the legs 9 are in the position illustrated in Figure 2 the machine is firmly 70 supported upon the floor and is preferably located at one side of a work table.

Wall paper in roll formation is mounted upon a rod 14 extended through the sides of the frame and a pair of guiding disks 15 75 are adjustably secured by means of set screws to the rod at opposite ends of the roll of wall paper. Figures 1 and 3 illustrate that the guiding disks 15 are formed with forwardly extending tapered arms 18 80 which extend along the edges of the paper and guide the paper onto a paste applying roller 20. Before proceeding to describe the paste applying roller 20 and its operation it is desired to direct attention to Figures 85 1 and 4 which illustrate that the roll supporting rod 14 is detachably connected to the depending supporting members 22 at opposite sides of the frame. The several depending supporting members or gusset 90 plates, as the same may be called are formed with V-shaped recesses 24 which terminate in vertical slots 25 through which the rod 14 may be extended. It will be seen that by forcing the rod upwardly from within the slots 25 the rod may be readily detached from the machine for the purpose of allowing another roll of paper to be applied or inserted into the machine for use.

The paste applying roller 20 is provided 100 with a shaft 26 extended through the slotted lower portions 27 of the depending brackets 28 and it will be seen that the brackets 28 are formed with V-shaped recesses 29 communicating with the slots 27 so that the paste applying roller 20 may also be removed as the occasion requires.

The paste applying roller 20 is located 110 within an elongated paste containing receptacle 30, the ends of which are formed with hinged handles 32 for engagement with bars or attaching rods 33 secured to the opposite

ends of the frame. It is desired to point out that the attaching hooks 32 may be disconnected from the attaching rods 33 to allow the container 30 to be lowered to the floor 5 for the purpose of filling the same or partly filling the same with paste. When the receptacle 30 is in position the rotation of the roller 20 will cause a quantity of the paste to be applied to the roller for subsequent application to the paper. The paste is thus uniformly and thoroughly applied to the under side of the paper so that the paper is in condition to be immediately applied to the wall.

15 As the paper passes over the paste applying roll 20 it engages the surface of an idler or tensioning roller 36 by means of which the contact of the paper with the roller 20 over a wide area of the latter is provided for.

20 The paper is urged into engagement with the paste applying roller 20 by means of a skeleton paper weight 40 the rear portion of which is formed with a hinge barrel 42 for the reception of a hinged rod 43, the said 25 hinge rod being connected to the ends of the frame in any suitable manner.

In use the skeleton paper weight 40 is pressed into engagement with the paper by spring pressure and the further application 30 of the paste to the under side of the paper is provided for.

As the paper is unrolled the same is cut longitudinally by one or more knives 50 secured by means of set screws 52 to a knife carrying bar 54. The set screws hold the cutters 56 of the knives in engagement with the paper and when the set screws 52 are released the knives may be swung rearwardly by turning the same upon the rod or bar 40 54 into engagement with the handle 58.

To aid in the adjustment of the knives 50 a rule 60 is extended across the frame and is secured to the same by means of angle bars or brackets 62. The desired calculation 45 may be made by means of calibrations or indications on the rule 60 and the paper may thus be cut to the desired width.

A machine constructed in accordance with 50 this invention provides an extremely simple means whereby the paper may be simultaneously pasted and cut to the desired width. Furthermore, paper hanging is greatly facilitated as it is not necessary to manually apply the paste with a brush as is now done.

55 Of course suitable provision is made for matching patterns of the paper and as the paper is pasted the same is severed along a straight line so that it may be hung on the wall.

60 One of the principal advantages of this machine resides in the fact that it may be conveniently set up and transported from place to place and that it quickly and expeditiously applies the paste and cuts the 65 paper along the proper lines.

Having thus described the invention, what is claimed is:

1. A paper pasting and cutting machine comprising a frame having depending brackets, a paste applying roller having a shaft connected to said brackets, a paste containing receptacle receiving said roller and having detachable connection with said frame, a paper supporting rod carried by said frame, guide members mounted on said rod and having forwardly projecting arms to engage the edges of the paper and thereby guide the same over the paste applying roll, and means to urge the paper into contact with the roll. 80

2. A machine of the character specified comprising a frame, a paste applying roll having a shaft, said frame being provided with brackets having V-shaped openings terminating in vertical slots receiving the ends of said shaft, a paste containing receptacle having hooks hingedly connected thereto and adapted for engagement with the frame, and means whereby to urge the paper flatly into contact with the roll. 90

3. A machine of the character specified comprising a frame, a paste applying roll having a shaft, said frame being provided with brackets having openings terminating in vertical slots receiving the ends of said shaft, a paste containing receptacle having hooks hingedly connected thereto and adapted for engagement with the frame, means whereby to urge the paper flatly into contact with the roll, paper supporting rods carried by said frame and having guide disks adjustable thereon and provided with forwardly directed arms engaging the edges of the paper to guide the paper, and a second roller carried by said frame and adapted for engagement by the paper. 100

4. A machine of the character specified comprising a frame, a paste applying roller having a shaft, said frame being provided with depending brackets having V-shaped openings terminating in vertical slots receiving the ends of said shaft, a paste containing receptacle having hooks hingedly connected thereto and adapted for engagement with the frame, means whereby to urge the paper flatly into contact with the roller, paper supporting means carried by said frame and having guide disks adjustable thereon and provided with forwardly directed arms engaging the edges of the paper to guide the paper, a second roller carried by said frame and adapted for engagement by the paper, a knife bar carried by said frame and having a pair of cutters adjustable thereon for cutting the paper longitudinally between the roller for applying the paste and the roll of paper. 115 120

5. A machine of the character specified comprising a frame, a paste applying roller having a shaft, said frame being provided 130

- with depending brackets having V-shaped openings terminating in vertical slots receiving the ends of said shaft, a paste containing receptacle having hooks hingedly connected thereto and adapted for engagement with the frame, means whereby to urge the paper flatly into contact with the roller, paper supporting rods carried by said frame and having guide disks adjustable theron and provided with forwardly directed arms engaging the edges of the paper to guide the paper, a second roller carried by said frame and adapted for engagement by the paper, a knife bar carried by said frame and having a pair of cutters adjustable thereon for cutting the paper longitudinally between the roller for applying the paste and the roll of paper, and collapsible means to support the frame.
6. A machine of the character described comprising a frame having brackets formed with slots, a paste-applying roller having a shaft received in said slots, a paste containing receptacle having hooks hinged thereto and adapted for connection with the frame, paper supporting means carried by said frame and having guide members adjustable thereon and provided with arms engaging the edges of the paper to guide the paper, and a second roller carried by said frame and adapted for engagement by the paper.
7. A machine of the character described comprising a frame having brackets formed with slots, a paste-applying roller having a shaft received in said slots, a paste containing receptacle having hooks hinged thereto and adapted for connection with the frame, paper supporting means carried by said frame and having guide members adjustable thereon and provided with arms engaging the edges of the paper to guide the paper, a second roller carried by said frame and adapted for engagement by the paper, and means to urge the paper flatly into contact with the paste applying roller.

RAOUL J. PARATORE.
